United States Patent Office

Des. 217,943
Patented June 30, 1970

217,943

BOOT TREE

Frederick Francis Dunkelman, Desborough, England
Filed Aug. 12, 1968, Ser. No. 13,110

Claims priority, application Great Britain Mar. 21, 1968

Term of patent 14 years

Int. Cl. D4—02

U.S. Cl. D86—10

Fig. 1

Fig. 2

Fig. 3

FIG. 4

FIG. 1 is a side perspective view of a boot tree showing my new design;

FIG. 2 is a side elevational view of the boot tree shown in FIG. 1, both sides being the same;

FIG. 3 is a top plan view thereof; and

FIG. 4 is a side perspective view of a second embodiment of the design shown in FIG. 1.

I claim:

The ornamental design for a boot tree, substantially as shown and described.
